UNITED STATES PATENT OFFICE.

JAMES NEIL, OF WASHINGTON, DISTRICT OF COLUMBIA, ASSIGNOR OF ONE-HALF TO
JOHN F. RUSSELL, OF WASHINGTON, DISTRICT OF COLUMBIA.

HORSESHOE.

1,191,984.

Specification of Letters Patent. Patented July 25, 1916.

Application filed November 17, 1915. Serial No. 61,879.

To all whom it may concern:

- Be it known that I, JAMES NEIL, a citizen of the United States, residing at Washington, in the District of Columbia, have invented certain new and useful Improvements in Horseshoes; and I do declare the following to be a full, clear, and exact description of the invention, such as will enable others skilled in the art to which it appertains to make and use the same, reference being had to the accompanying drawings, and to the letters and figures of reference marked thereon, which form a part of this specification.
- This invention relates to horse shoes and has for its object to provide a device of this class which is particularly adapted to be used on horses, and mules when the same are doing extremely heavy draft work and under unfavorable conditions such as in snow, ice or mud.
- A further object of the invention is to provide a horse shoe which is so constructed and arranged that it will quickly and effectually relieve itself of an accumulation of snow, ice or mud commonly termed "balling," to such an extent that the shoe under the most unfavorable conditions is maintained in a high state of efficiency.
- A further object of this invention is to provide an anti-slipping horse shoe, so constructed and arranged that it retains its anti-slipping qualities during practically the entire life of the shoe.
- A further object of the invention is to provide a horse shoe which while preferably forged can be quickly fitted and if desired can be fitted cold according as the mechanic desires.
- A further object of this invention is to provide a horse shoe which will wear for an exceptional length of time, is simple in its construction, cheap and easy to manufacture, strong, durable and efficient.
- With these and other objects in view the invention consists in the novel construction and arrangement of the shoe, and particularly in the construction and arrangement of the calks for preventing the accumulation of snow, ice or mud and the retention of the same therein.
- The invention further consists in certain combinations of parts, all of which will be first fully described and afterward specifically pointed out in the appended claim.

Referring to the accompanying drawings: Figure 1 is a bottom plan view of a horse shoe constructed in accordance with this invention. Fig. 2 is a side elevation of the same. Fig. 3 is a transverse sectional view taken on line 3—3 of Fig. 1 and Fig. 4 is a sectional view taken on line 4—4 of Fig. 1. Like numerals of reference indicate the same parts throughout the several figures in which:

1 indicates the shoe which includes the body of the shoe shaped substantially as shown in which 2 indicates the toe portion and 3 the two heel portions. Depending from the body 1, at the heel portions 3 is a plurality or series of transverse calks 4 having relatively large bases 5 and reduced faces 6, the same being so formed as to provide an excessive "draft" for the calks to prevent the anchoring of accumulated snow, ice or mud between and about the same.

7 indicates the main body calk which as will appear from the drawing merges into the foremost transverse heel calk 4 at the rear end and which merges into the toe calk 8 at its toe end, a relatively short connecting wall 9 being provided as shown so as to cause a perfectly continuous structure to prevent the anchoring of accumulated snow, ice or mud about the same. As will appear from the drawing the main body calk 7, toe calk 8 and connecting walls 9 are provided with relatively wide bases 10 and a narrow continuous face 11, this construction providing excessive "draft" to the parts to prevent the accumulation and retention of snow, ice or mud in and about the same.

As will appear from Fig. 1, the formation of the toe calk 2 in connection with the connecting walls 9 and main body calk 7, provides a chamber 12 at the toe portion of the shoe causing a break in continuity of any accumulation within the shoe so that the shoe will quickly free itself thereof, while the continuous face 11 of the main body calk 7, toe calk 8 and connecting walls 9 presents a maximum area to effectually prevent the shoe or portions thereof from entering slots, cracks or crevices in thoroughfares, roadways or the like which are at all times dangerous to horses shod with shoes of ordinary design.

As will appear from Figs. 1 and 3 the shoe is provided with a suitable number of nail openings 13 located in the face 14 of the

body between the base 10 of the main body calk 7 and the outer edge 15 of the shoe, while a suitable toe projection 16 is provided as is usual.

5 Having thus fully described the several parts of this invention it is apparent that the same is susceptible to certain changes in the construction and arrangement of the parts, and I consider myself clearly entitled to all such changes and modifications as fall within the limit and scope of the appended claim.

What I claim as new and desire to secure by Letters Patent of the United States is:

15 A horse shoe including a main body having a toe portion and heel portions, a plurality of transverse calks at the heel portions spaced apart, each of which is provided with a relatively wide base and a narrow face to prevent the anchoring of accumulations therebetween, a main body calk 20 formed on a regular curve conforming substantially to the contour of the body, said

main body calk being disposed on the body so as to present a supporting surface relatively narrow with respect to the body of the shoe and lying about centrally of said body, the heel end of said main body calk merging into the foremost of said transverse heel calks, a toe calk, a connecting wall connecting with each end of said toe calk, the said main body calk merging into the connecting walls, said main body calk, toe calk and connecting walls being provided with relatively wide bases and a narrow continuous face, said formation providing a chamber at the toe portion of the shoe to break the regularity between the said main body calk and the toe calk, substantially as described.

In testimony whereof, I affix my signature, in presence of two witnesses.

JAMES NEIL.

Witnesses:

FLORENCE A. BARRON,
C. HUGH DUFFY.
